UNITED STATES PATENT OFFICE

WILLIAM L. PAUL, OF BERKELEY, CALIFORNIA, ASSIGNOR TO DEERE AND COMPANY,
OF MOLINE, ILLINOIS, A CORPORATION OF ILLINOIS

DISK HARROW

Application filed November 13, 1925, Serial No. 68,835. Renewed October 3, 1929.

My invention relates to disk harrows designed to be drawn by a tractor, and has particularly to do with the provision of means by which the power of the tractor may be utilized in varying the angular position of the disk gangs. Heretofore this has been accomplished in various ways, as for example by backing the tractor and the harrow along with it, to straighten the gangs, or by mechanism actuated by the forward movement of the harrow. While the prior devices have been measurably successful, certain conditions are often encountered in the use of such implements in which they do not operate satisfactorily, as for instance, where the tractor has mired so that it is unable to move the load in addition to its own weight. The object of my invention is to provide an improved construction by which both the angling and the straightening of the gangs may be accomplished by forward movement of the tractor relatively to the harrow frame and the disk gangs connected therewith, so that the work may be performed without the necessity of moving the harrow along with the tractor. Consequently, if the tractor should be mired it has only its own weight to move, and is, therefore, more apt to extricate itself. My invention also contemplates the backing of the tractor relatively to the harrow as the first step in the operation of varying the angular position of the gangs, by which operation it operates to roll down any soft spot by which it may have been stalled, thereby providing a firmer path for it to traverse in going ahead again, which usually will enable it to haul the harrow over the soft spot, especially if the gangs have been straightened, or have been set at a reduced angle. I accomplish my objects as illustrated in the accompanying drawings and as hereinafter described. What I regard as new is set forth in the claims.

In the accompanying drawings,—

Fig. 1 is a plan view of a disk harrow embodying my improvements, some parts being broken away;

Fig. 2 is a side elevation thereof showing the gangs straightened, or in transport position, with the harrow coupled to a tractor;

Fig. 3 is a longitudinal vertical section on line 3—3 of Fig. 1 showing the parts in the position they occupy after the tractor has been backed and just before it is advanced to change the angle of the disk gangs; 55

Fig. 4 is a vertical cross-section on line 4—4 of Fig. 6;

Fig. 5 is a side elevation, some parts being in section, showing the position of the parts when the gangs are in transport position; 60

Fig. 6 is a horizontal section on line 6—6 of Fig. 3;

Fig. 7 is a vertical cross-section on line 7—7 of Fig. 5; 65

Fig. 8 is a view similar to Fig. 5 showing the parts in the position they occupy when the gangs are angled to the fullest extent;

Fig. 9 is an enlarged detail showing a combined gear and ratchet wheel and a disk 70 which constitute part of the gang shifting mechanism; and

Fig. 10 is a section on line 10—10 of Fig. 9.

Referring to the drawings,—11 indicates 75 the tractor, which is provided with a draw bar 12 to which the harrow is hitched in any suitable way, as by a clevis 13. The harrow comprises the usual disk gangs 14, 15 which are pivotally connected by vertical pivots 16, 17 to rearwardly projecting members 18, 19 of the harrow frame, which comprises a transverse member 20, and parallel members 21, 22 which extend forward from the central portion of the member 20 80 at opposite sides of the median line of the harrow and are braced by braces 23, 24, respectively. The members 20, 21, 22, 23 and 24 are preferably steel bars rectangular in cross-section. At or near their forward ends the bars 21, 22 carry a bracket comprising side plates 25, 26 secured to the said bars, said side plates being connected by a transverse plate 27 that is disposed transversely under the bars 21, 22, as 85 best shown in Fig. 4. Said plate 27 is provided with two openings 28, 29 for the reception of guide bars 30, 31 which serve the cause the gangs to travel in a horizontal plane and also to connect the inner ends of 90

95

100

the disk gangs with the angling devices, as will be hereinafter more fully explained.

Supported on said bracket above the plate 27 to slide longitudinally of the harrow is 5 a draft bar 32 which at its front end is connected with the clevis 13 by a horizontal pivot 33, as shown in Fig. 1. The side margins of said draft bar lie between the bars 21, 22 and shoulders 34, 35 on the bracket above mentioned above the plate 27, 10 as shown in Fig. 4, so that said draft bar is guided by the bracket as it moves fore and aft. The draft bar 32 is provided at its upper side with a longitudinally extending rack bar 36, as best shown in Figs. 4 15 and 6.

As shown in Fig. 1, the rear ends of the 20 guide bars 30, 31 are connected with the inner end portions of the disk gangs 14, 15, respectively, by pivots 37, 38, so that fore and aft movement of said guide bars operates to swing the gangs about the pivots 16, 17, thereby changing their angular relation to the line of draft. Pivots connected with the rear portions of said bars 25 30, 31, respectively, by pivots 39, 40 are links 41, 42, which extend forward between said bars and at their forward ends are connected by a pivot 43 with the lower end of 33 a link 44 arranged to swing fore and aft in a vertical plane. The upper end of the link 44 is connected by a pivot 45 with an arm 46 that depends from a lever 47 fulcrumed at 48 on the machine frame, preferably by means of a bracket 49, as shown in 38 Fig. 5. The lever 47 is provided with the usual latch 50 which engages with the notches of a sector 51 also mounted on the bracket 49. It will be apparent, therefore, 40 that by swinging the lever 47 up or down the link 44 will be moved vertically, thereby swinging the forward ends of the links 41, 42 up or down. The pivot 43 extends through an arcuate slot 52 in a yoke 53 which 45 is pivoted at its upper end to the sector 51, or some other fixed part of the frame, by a pivot 54, as shown in Fig. 5. The lower end of the yoke 53 may, therefore, swing fore and aft, carrying with it the pivot 43 and 50 consequently moving the links 41, 42 endwise. This movement is, of course, communicated to the guide bars 30, 31, and through them is transmitted to the inner ends of the disk gangs. It will be evident, 55 therefore, that by swinging the yoke 53 in the manner described the angular position of the gangs may be adjusted, and that by moving the link 44 vertically to move the pivot 43 vertically in the slot 52, the extent to 60 which the gangs will be adjusted by a given movement of the yoke 53 may be varied. The arcuate slot 52 is curved in the arc of a circle of which the pivots 39, 40 of the links 41, 42 are at the center when the gangs 65 are alined, that is, when the yoke 53 is in its

forwardmost position. Thus, regardless of the position of the pivot 43 in the slot 52, the forward movement of the yoke brings the gangs to their alined or transport position. Consequently when the gangs are 70 alined with each other, which is the position shown in Fig. 5, the lever 47 may be actuated to adjust the position of the pivot 53 without altering the position of the gangs, but when the gangs are angled, actuation 75 of the lever 47 alters their position to some extent.

Provision is made for swinging the yoke 53 fore and aft by the power of the tractor to vary the angular position of the gangs, and 80 the devices by which that is accomplished will now be explained. Referring particularly to Figures 5, 9 and 10, it will be seen that a pitman 55 is pivotally connected at its rear end by a pivot 56 with the yoke 53, its 85 forward end being connected by a wrist pin 57 with an arm 58 extending radially beyond the periphery of a disk 59 which is journaled on a transverse shaft 60 carried by a bracket 61 which rises from the forward portion of the harrow frame. Mounted concentrically with the disk 59 on the shaft 60 is a combined gear and ratchet wheel 62 recessed at one side to receive the disk 59, and provided with suitable clutch mechanism by which rotation of said wheel in one direction will cause corresponding rotation of the disk 59, whereas said wheel may rotate in the opposite direction independently of said disk. For this purpose preferably said wheel is 90 provided with internal ratchet teeth 63 which overlie the periphery of said disk, as best shown in Fig. 10. On its periphery the wheel 62 is provided with gear teeth 64 which preferably extend only part way around said wheel, as best shown in Fig. 9. A pawl 65 is pivotally mounted on the disk 59 by means of a pivot 66 and is normally held in engagement with the ratchet teeth 63 by a spring 67. The arrangement is such that the wheel 62 95 may rotate counterclockwise as viewed in Fig. 9 independently of the disk 59, but when said wheel rotates clockwise the disk 59 rotates with it. The disk 59 is provided with a second arm 68 which projects radially therefrom at a point approximately opposite the arm 58. The arm 68 carries a rounded head or roller 69 at one side thereof, and the outer end of the arm 58 is also rounded so that it also forms a head 70 similar to the 100 head or roller 69. The parts 69, 70 are adapted to engage in a rounded notch 71 provided in the lower end of a trip lever 72 which is fulcrumed on the harrow frame by pivot 73, preferably by means of a bracket 74 rising 105 from the frame, as shown in Fig. 5. The lower end of said lever is yieldingly held in proximity to the wheel 62 by means of a spring 75 interposed between the lower end of said lever and a lug 76 carried by the 110

bracket 74, as best shown in Fig. 3. As shown in Figs. 1, 3 and 5, the rack bar 36 is arranged to move longitudinally of the machine under the wheel 62, with the teeth of which it is constantly in mesh. When, therefore, said rack bar is moved longitudinally in one direction or the other it rotates the wheel 62. Forward movement of the rack bar rotates said wheel in a clockwise direction as viewed in Figs. 3 and 9, and consequently rotates the disk 59 with it, whereas rearward movement of said rack bar rotates the wheel 62 in a counterclockwise direction, leaving the disk 59 stationary. As best shown in Fig. 3, said rack bar is provided on its rear portion with a downwardly projecting lug 77 which is adapted to engage the rear margin of a bottom plate 78 that connects the side members 21, 22 of the bracket by which said draft bar is supported, thereby limiting the forward movement of said draft bar and transmitting the force of the draft to the harrow frame through said bracket. Normally said draft bar stands in the position shown in Fig. 5, at which time it is at the forward limit of its movement with the lug 77 in engagement with the rear margin of the bottom plate 78. The other parts are also then in the position shown in Fig. 5, the head 70 being in engagement with the notch 71 of the trip lever 72, the lower end of said lever lying in the path of the draft bar opposite the rear end thereof, as shown at 79 in said figure. At that time the pitman 55 is in practically dead center position, since the pivots 56 and 57 are in line with the axis of the disk 59 and wheel 62, and the lever 72 being pressed by the spring 75 effectively holds the gangs in either their angled or their transport position.

With the parts in the position shown in Fig. 5, the harrow may be drawn forward with the gangs in transport position, draft being transmitted to the harrow frame through the lug 77 as above stated. If it be desired to angle the gangs, this may be done by pulling forward on the upper end of the trip lever 72, which for that purpose is preferably provided with a rope or cable 80 extending to the tractor. When the trip lever 72 is so actuated its lower end is swung rearwardly to release the head 70 from the notch 71 and permit the disk 59 to rotate. A spring 81, one end of which is connected with the pitman 55 and the other end with the upper portion of the yoke 53, tends to swing the forward end of said pitman upward, and consequently to rotate the disk 59 in a clockwise direction. Therefore, when the disk is released by the tripping of the lever 72 as above described, the forward movement of the implement will cause the gangs to angle, since their inner ends will be held back by friction with the soil while their outer ends will be drawn forward. In this angling oper-

ation the pitman 55 will be moved endwise, swinging the lower end of the yoke 53 rearwardly to the position shown in Fig. 8. This angling movement will be arrested as soon as the disk 59 makes a half revolution, at which time the roller or head 69 will be caught in the notch 71 of the lever 72, thereby preventing further rotation of said disk. As the gangs are angled the guide bars 30, 31 move endwise in a rearward direction, their forward ends being guided by the plate 27, while their rear ends are guided by rollers 82, 83 mounted on the frame of the harrow, as best shown in Figs. 1 and 5. These rollers bear on the upper margins of said guide bars and cooperate with the plate 27 to cause the gangs to maintain their horizontal position. The extent to which the gangs are angled may be regulated by operating the lever 47 to raise or lower the link 44 with reference to the yoke 53, thereby moving the pivot 43 toward or from the pivot 54 about which said yoke swings. Obviously when the pivot 43 is at its extreme distance from the pivot 54 the stroke of the links 41, 42 will be greatest and the gangs will be angled to the fullest extent, and by moving the pivot 43 closer to the pivot 54 the stroke of said links will be reduced in length and the gangs will consequently be angled to a less extent.

If, instead of angling the gangs by the forward travel of the harrow, it be desired to effect such angling by the power of the tractor independently of movement of the harrow frame, this may be done by first backing the tractor to move the draft bar 32 rearwardly to the position shown in Fig. 3. This rotates the gear wheel 62 in a counterclockwise direction and at the same time the engagement of the rear end of the draft bar 32 with the lower end of the trip lever 72 will move such lower end rearwardly thereby disengaging it from the head 69 as shown in Figure 3. By then advancing the tractor the draft bar 32 will rotate the gear wheel 62 in a clockwise direction, rotating the disk 59 in the same direction by reason of the ratchet connection between said disc and the wheel 62. This will positively move the pitman 55 rearwardly, thereby forcing the links 41, 42 and the guide bars 30, 31 in the same direction, which moves the inner ends of the gangs backward. When the disc 59 has made a half revolution it will be locked by the trip lever 72 in the manner above described. In like manner the gangs may be straightened by first backing the tractor to rotate the wheel 62 counterclockwise and then advancing the tractor to rotate the disk 59 through the second half of its cycle, which will move the pitman 55 forward and restore the parts to the position shown in Fig. 5.

It is believed that it will be clear from the foregoing description that by the construction described the gangs may be angled or

straightened by forward movement of the tractor independently of the harrow proper, these operations being performed alternately; also that the gangs may be angled by forward movement of the harrow along with the tractor. If, therefore, the tractor should become mired with the gangs in their angled position, by backing the tractor it will roll down the earth, thereby hardening it so that on the succeeding forward movement of the tractor it will advance over hardened earth and at the same time will straighten the gangs so that they will offer less resistance, thereby enabling the tractor to extricate itself.

If it be desired to vary the extent to which the gangs are angled, this may be accomplished by adjusting the position of the lever 47 to raise or lower the pivot 43 with respect to the yoke 53, as has been described.

While I have shown my invention as applied to a harrow comprising only two disk gangs obviously it may also be applied to tandem disk harrows. I wish it to be understood, further, that while I have described specifically the construction illustrated in the drawings, my invention is not limited to that particular construction, but includes such variations or modifications as would occur to those skilled in the art. The claims hereinafter made are therefore to be construed accordingly.

What I claim as my invention and desire to secure by Letters Patent, is—

1. A gang shifting mechanism for disk harrows, comprising a draft member movable fore and aft relatively to the harrow frame, and means comprising rotary clutch controlled devices actuated by movement of said draft member to adjust the angular position of the gangs.

2. A gang shifting mechanism for disk harrows, comprising a draft member movable rearwardly independently of the gangs, and means comprising rotary clutch controlled devices actuated by forward movement of said draft member to shift the gangs angularly in either direction.

3. A gang shifting mechanism for disk harrows, comprising a draft member movable fore and aft relatively to the harrow frame, and rotary means constantly in operative connection with and actuated by alternate forward movements of said draft member to alternately angle and straighten the gangs.

4. A gang shifting mechanism for disk harrows, comprising a draft member movable fore and aft relatively to the harrow frame, and means comprising rotary ratchet mechanism in constant engagement with, and actuated by said draft member to vary the angular position of the gangs in either direction.

5. A gang shifting mechanism for disk harrows, comprising a draft member mov-

able fore and aft relatively to the harrow frame, a pitman connected with the gangs and operable to change the angular position thereof, and rotatable means actuated in a constant direction by fore and aft movement of said draft member relatively to the harrow frame for actuating said pitman.

6. A gang shifting mechanism for disk harrows, comprising a draft member movable fore and aft relatively to the harrow frame, a pitman connected with the gangs and operable to change the angular position thereof by forward pulling movement and rearward thrusting movement, and rotary clutch mechanism actuated by fore and aft movement of said draft member relatively to the harrow frame for actuating said pitman.

7. A gang shifting mechanism for disk harrows, comprising a draft member movable fore and aft relatively to the harrow frame, a pitman connected with the gangs and operable to change the angular position thereof, and rotary ratchet devices operatively connected with said draft member and actuated to operate said pitman by forward movement only of said draft member relatively to the harrow frame.

8. A gang shifting mechanism for disk harrows, comprising a draft member movable fore and aft relatively to the harrow frame, a pitman connected with the gangs and operable to change the angular position thereof, and rotary means having constant operative connection with said draft member and actuated by forward movement only thereof relatively to the harrow frame to operate said pitman.

9. A gang shifting mechanism for disk harrows, comprising a draft member movable fore and aft relatively to the harrow frame, a pitman connected with the gangs and operable to change the angular position thereof, and rotary clutch mechanism actuated by forward movement only of the draft member relatively to the harrow frame to pull said pitman forwardly or to thrust the same rearwardly.

10. A gang shifting mechanism for disk harrows, comprising a draft member movable fore and aft relatively to the harrow frame, a rotary member mounted on the harrow frame, means actuated by the rotation of said rotary member in a constant direction for adjusting the angular position of the gangs in either direction, and means actuated by movement of said draft member to rotate said rotary member.

11. A gang shifting mechanism for disk harrows, comprising a draft member movable fore and aft relatively to the harrow frame, a rotary disk mounted on the harrow frame, means actuated by partial rotation of said disk for shifting the gangs in one direction and by further rotation of said disk in the same direction to shift the gangs in the

opposite direction, and means for rotating said disk by movement of said draft member.

12. A gang shifting mechanism for disk harrows, comprising a draft member movable fore and aft relatively to the harrow frame, a rotary member mounted on the harrow frame, means actuated by the rotation of said rotary member in a constant direction for adjusting the angular position of the gangs in either direction, and means actuated by movement of said draft member in one direction only to rotate said rotary member.

13. A gang shifting mechanism for disk harrows, comprising a draft member movable fore and aft relatively to the harrow frame, a rotary member mounted on the harrow frame, means actuated by the rotation of said rotary member in a constant direction for adjusting the angular position of the gangs in either direction, and means actuated by forward movement only of said draft member to rotate said rotary member.

14. A gang shifting mechanism for disk harrows, comprising a draft member movable fore and aft relatively to the harrow frame, a pitman connected with the gangs and operable to change the angular position thereof, and rotatable ratchet devices actuated by forward movement only of the draft member relatively to the harrow frame to actuate said pitman.

15. A gang shifting mechanism for disk harrows, comprising a draft member movable fore and aft relatively to the harrow frame and having a rack thereon, a gear meshing with said rack, a disk, ratchet mechanism for driving said disk from said gear, and means actuated by the rotation of said disk for changing the angular position of the gangs.

16. A gang shifting mechanism for disk harrows, comprising a draft member movable fore and aft relatively to the harrow frame and having a rack thereon, a gear meshing with said rack, a disk, ratchet mechanism for driving said disk from said gear, and means actuated by partial rotation of said disk for shifting the gangs in one direction, and by further rotation of said disk in the same direction to shift the gangs in the opposite direction.

17. A gang shifting mechanism for disk harrows, comprising a draft member movable fore and aft relatively to the harrow frame and having a rack thereon, a gear meshing with said rack, a disk, ratchet mechanism for driving said disk from said gear, and a pitman actuated by said disk and connected with the gangs for adjusting their angular position.

18. A gang shifting mechanism for disk harrows, comprising a draft member movable relatively to the harrow frame by forward and backward movement of the tractor relative to the harrow frame, means com-

prising clutch controlled devices actuated by movement of said draft member for adjusting the angular position of the gangs, and means operable to vary the angular movement of said gangs effected by a given movement of said draft member.

19. A gang shifting mechanism for disk harrows, comprising a draft member movable relatively to the harrow frame and through which the draft is transmitted to said frame, means comprising clutch controlled devices actuated by forward movement of said draft member to adjust the angular position of the gangs, and means operable to vary the adjustment of said gangs effected by a given movement of said draft member.

20. A gang shifting mechanism for disk harrows, comprising a draft member movable relatively to the harrow frame by forward and backward movement of the tractor relatively to the harrow frame, means comprising clutch controlled devices actuated by movement of said draft member for adjusting the angular position of the gangs, and means operable to vary the angular movement in either direction of said gangs effected by a given movement of said draft member.

21. A gang shifting mechanism for disk harrows, comprising a draft member reciprocal relatively to the harrow frame and through which the draft is transmitted to said frame, means comprising clutch controlled devices actuated by forward movement of said draft member to adjust the angular position of the gangs, and means operable to vary the adjustment in either direction of said gangs effected by a given movement of said draft member.

22. A gang shifting mechanism for disk harrows comprising a draft member movable relatively to the harrow frame, devices actuated by movement of said draft member for adjusting the angular position of the gangs, a lever mounted on the harrow frame, and means operated by said lever for governing the extent of movement of said devices effected by a given movement of said draft member.

23. In a gang shifting mechanism for disk harrows, the combination of a draft member movable relatively to the harrow frame, and devices actuated by movement of said draft member for adjusting the angular position of the gangs comprising a member pivoted to swing fore and aft and actuated by said draft member, and links connected with the disk gangs and actuated by said swinging member to adjust the angular position of the gangs, said links being adjustable toward and from the pivot of said swinging member to vary the angular movement of the gangs effected by a given movement of said draft member.

24. In a gang shifting mechanism for disk harrows, the combination of a draft member movable relatively to the harrow frame, and devices actuated by movement of said draft member for adjusting the angular position of the gangs comprising a member pivoted to swing fore and aft and actuated by said draft member, and links connected with the disk gangs and actuated by said swinging member to adjust the angular position of the gangs, said links being adjustable toward and from the pivot of said swinging member to vary the angular movement of the gangs effected by a given movement of said draft member, and a lever mounted on the harrow frame and operable to adjust the position of said links with reference to said swinging member.

25. In a gang shifting mechanism for disk harrows, the combination of a draft member movable relatively to the harrow frame, and devices actuated by movement of said draft member for adjusting the angular position of the gangs comprising a yoke pivoted on the harrow frame to swing fore and aft and actuated by movement of said draft member, said yoke having an arcuate slot, links connected with the disk gangs and having a connection extending through said slot, and means mounted on the harrow frame and operable to move said links toward and from the pivot of said yoke to vary the angular movement of the gangs effected by a given movement of the draft member.

35. 26. A gang shifting mechanism for disk harrows, comprising a draft member movable fore and aft relatively to the harrow frame, and connecting means between said member and gangs and operable upon fore and aft movement of the draft member to shift said gangs to and from transport position, said connecting means including adjustable means for varying the angular movement of the gangs effected by a given movement of the draft member.

27. A gang shifting mechanism for disk harrows, comprising a draft member movable fore and aft relatively to the harrow frame, connecting means between said member and gangs and operable upon fore and aft movement of the draft member to shift said gangs to and from transport position, said connecting means including adjustable means for varying the angular movement of the gangs effected by a given movement of the draft member, and releasable means to lock said gangs in shifted position.

28. A gang shifting mechanism for disk harrows, comprising a draft member movable fore and aft relatively to the harrow frame, connecting means between said member and gangs and operable upon fore and aft movement of the draft member to shift said gangs to and from transport position, said connecting means including adjustable means for

varying the angular movement of the gangs effected by a given movement of the draft member, and releasable means to lock said gangs in shifted position, means for releasing the locking means upon backward movement 70 of said draft member.

29. A gang shifting mechanism for disk harrows, comprising a draft member movable fore and aft relatively to the harrow frame, means comprising clutch controlled devices 75 actuated by movement of said draft member for moving said gangs of disks to and from transport position, adjustable means operable to vary the angular movement of said gangs effected by a given movement of the 80 draft member, said first mentioned means bringing said gangs to the same transport position regardless of the position of said adjustable means.

30. In a gang shifting mechanism for disk 85 harrows, the combination of a draft member movable relatively to the harrow frame, and devices actuated by movement of said draft member for adjusting the angular position of the gangs comprising a yoke pivoted on the harrow frame to swing fore and aft and actuated by movement of said draft member, said yoke having an arcuate slot, links connected with the disk gangs and having a connection 90 extending through said slot, and means mounted on the harrow frame and operable to move said links toward and from the pivot of said yoke to vary the angular movement 95 of the gangs effected by a given movement of the draft member, said links being so pivoted, relative to the yoke, that when the yoke is in its forward position the pivot of said links substantially coincides with the center of said arcuate slot, whereby forward movement of the yoke brings the gangs to the same position 100 irrespective of the position of said last mentioned means.

31. A gang shifting mechanism for disk 110 harrows, comprising a draft member movable relatively to the harrow frame, means including rotary clutch controlled devices actuated by movement of said draft member to adjust the angular position of the gangs, and means to lock said gangs in adjusted position, said means being released upon movement in 115 one direction of said draft member relatively to the harrow frame.

32. A gang shifting mechanism for disk 120 harrows, comprising a draft member movable relatively to the harrow frame and through which the draft is transmitted to said frame, means including clutch controlled devices actuated by movement of said draft member to adjust the angular position of the gangs, means operable to vary the adjustment of 125 said gang effected by a given movement, and means to hold said gangs in adjusted position.

33. A gang shifting mechanism for disk 130 harrows, comprising a draft member mov-

able relatively to the harrow frame and through which the draft is transmitted to said frame, means including clutch controlled devices actuated by movement of said draft member to adjust the angular position of the gangs, means operable to vary the adjustment of said gang effected by a given movement, and means to hold said gangs in adjusted position, said means being released upon backward movement of said draft member.

5 34. A gang shifting mechanism for implements, comprising a draft member movable relatively to the frame of the implement, half-revolution clutch means actuated by relative movement of said draft member, releasable locking means to maintain said draft member in draft transmitting relation to said frame, and connecting means between said clutch means and the implements, whereby 10 when the locking means is released said implements are shifted.

15 35. A gang shifting mechanism for disk harrows, comprising a draft member movable relative to the frame of the implement, half revolution clutch means actuated by relative movement of said draft member, releasable locking means to maintain said draft member in draft transmitting relation to said frame, connecting means between said clutch 20 means and said gangs whereby when the locking means is released said gang means are shifted, said locking means being released by relative movement of said draft member in one direction.

25 36. A gang shifting mechanism for disk harrows, comprising a draft member movable fore and aft relatively to the harrow frame, connecting means between said member and said gangs operable upon fore and aft movement of said member to shift said gangs to and from transport position, said connecting means including an adjustable part for varying the movement of the gangs effected by a given movement of the draft member, and 30 means for adjusting said part.

40 37. A gang shifting mechanism for disk harrows, comprising a draft member movable fore and aft relatively to the harrow frame, connecting means between said member and said gangs operable upon fore and aft movement of said member to shift said gangs to and from transport position, said connecting means including a member movable to a fixed position when the draft member is moved in 45 one direction and adjustable link means connecting the movable member with the gangs, said link means connected to said movable member so that when the movable member is moved to its fixed position the gangs are moved to a given position independently of the adjustment of said link means.

55 38. A gang shifting mechanism for disk harrows, comprising a draft member movable fore and aft relatively to the harrow frame, connecting means between said member and

said gangs operable upon fore and aft movement of said member to shift said gangs to and from transport position, and releasable means to lock said gangs in shifted position.

39. A gang shifting mechanism for disk harrows, comprising a draft member movable with respect to the harrow frame, connecting means between the member and said gangs and operable upon movement of said member to shift said gangs, said connecting means including adjustable parts to vary the movement of the gangs effected by a given movement of said member and means to render the adjusting means ineffective when the gangs are in their transport position.

40. A disk harrow comprising, in combination, a frame, a plurality of gangs shiftable relatively thereto to and from inoperative position, a draft member movable fore and aft on the frame and between fixed limits, connections between the member and gangs including a pair of adjustable members adapted to vary the range of movement of said gangs effected by said member, and means to fix the inoperative position of said gangs.

41. A disk harrow comprising, in combination, a frame, gangs shiftable on the frame to and from a fixed transport position, a draft member movable fore and aft on the frame, operating connections between said member and the gangs whereby movement of the member shifts the gangs, and means in said connections to vary the amount of movement of the gangs from their fixed position effected by a given movement of said draft member.

42. A disk harrow comprising, in combination, a frame, gangs shiftable on the frame to and from a fixed transport position, a draft member movable fore and aft on the frame, operating connections between said member and the gangs whereby movement of the member shifts the gangs, said connections including a slotted member and means having a portion operating in said slot to vary the amount of movement of the gangs from their fixed position effected by a given movement of said draft member.

43. A disk harrow comprising, in combination, a frame, a plurality of gangs shiftable relatively thereto to and from inoperative position, a draft member movable fore and aft on the frame, and connections between the gangs and said member whereby movement of one effects movement of the other, said connections including a member movable in an arcuate path and a second member adjustably connected to the first member for varying the movement of the gangs effected by a given movement of the draft member by moving in a path which extended intersects said first path.

44. A disk harrow comprising, in combination, a frame, a plurality of gangs shiftable relatively thereto to and from inoper-

tive position, a draft member movable fore and aft on the frame, and connections between the gangs and said member whereby movement of one effects movement of the other, said connections including a member movable in an arcuate path and a second member movably connected to the gangs and to the first member to move with respect thereto in a path equidistant from the gangs in one of their shifted positions.

45. A disk harrow comprising in combination, a frame, a plurality of gangs shiftable relatively thereto to and from inoperative position, a draft member movable fore and aft on the frame, connections between the gangs and said member whereby movement of one effects movement of the other, said connections including a member movable in an arcuate path and a second member pivoted to the gangs and movably connected with the first member to move relatively thereto in a path which is equidistant from the point of pivotal connection of the second member with the gangs in one position, and 25 means to adjust said members.
